Primary Examiner—Alan P. Douglas*Assistant Examiner*—Robert M. Spear*Attorney, Agent, or Firm*—Davis, Bujold & Streck, P.A.[57] **CLAIM**

The ornamental design for a carrier/joining means for a series of packages, as shown and described.

DESCRIPTION

FIG. 1 is a top plan view of a carrier/joining means for a series of packages, showing our new design, the bottom plan view being a mirror image thereof;

FIG. 2 is an end elevational view thereof, the opposite end elevational view being a mirror image thereof; and,

FIG. 3 is a side elevational view thereof, the opposite side elevational view being a mirror image thereof.
